Daniel D. Minant.

UNITED STATES PATENT OFFICE.

D. D. WINANT, OF NEW YORK, N. Y., ASSIGNOR TO W. R. WINANT, OF BROOKLYN, NEW YORK.

BILLIARD-TABLE.

Specification of Letters Patent No. 22,001, dated November 2, 1858.

To all whom it may concern:

Be it known that I, DANIEL D. WINANT, of the city and State of New York, have invented, made, and applied to use certain 5 new and useful Improvements in Billiard-Tables; and I do hereby declare that the following is a full, clear, and exact description of the construction and operation of the same, reference being had to the annexed 10 drawing, making part of this specification, wherein—

Figure 1, is a vertical section of portions of the bed of my table and Fig. 2, is a plan of the device made use of to secure the bed 15 in place.

Similar marks of reference denote the same parts.

In the manufacture of billiard tables wood, slate and marble have been used for the 20 beds; the former however is objectionable on account of the shrinkage, warping and noise; the latter two are objectionable from the fact that hard spots very often exist in the marble or slate, so that when the beds are being 25 rubbed off to bring them true and level the said spots are not rubbed away and the sand produces a hollow or slight cavity around such hard places. To obviate this difficulty I make use of glass for the beds of billiard 30 tables, on account of its homogeneous nature causing it to rub down very evenly and also on account of the natural strength and elasticity possessed by the glass, rendering it especially available and beneficial for this 35 purpose, giving the ball a more lively action.

To hold down this glass onto the bed of the table occasioned some difficulty because the glass being brittle was apt to break if 40 screwed down. I therefore devised a metallic clip holding the glass in such a manner by projecting over the edge of the glass that was ground off or chipped to a bevel, that the glass was very firmly held in place; and those clips that come around the edge 45 in the places where screws are required for holding on the cushion rail I form of a solid metal block screwed onto the bed, and formed with a mortise receiving the nut and a hole to pass the screw, whereby the bed can be

close to the cushion rail so that the ball does 50 not pass off the bed in striking the cushion, and very much less noise is produced than in any bed with which I am acquainted.

In the drawing *a*, is the usual wood frame of the desired size and shape receiving the 55 slab, and these frames are to be adapted to sitting together in the usual way on the base of the table.

b, is the slab of glass, the edges of which are ground or dressed to a bevel at distances 60 of about two feet apart more or less around the edges, which bevels are about two inches in width and adapted to receive the metal clip *c*, that is formed to sit over the said inclined part of the edge and is screwed down 65 securely holding the glass to the bed; a sufficient number being applied around the edges of the glass for this purpose. The frame is then finished out level by the strip *d*, which also sustains the clips *c*. 70

At those places around the bed at which the screws of the cushion rails are to be inserted I make use of the metal block *e*, that is screwed on by the screws 1, 1, to the frame *a*, and answers a double purpose, viz., 75 to receive the said screw and its nut, and also to aid by the lip or clip 2, in keeping the slab (*b*) in place.

f, is the cushion rail of any suitable construction, and *g* is the screw passing through 80 said rail and into a hole in the said block *e*.

3, is the nut, dropped into a mortise in said block *e*, and into which the screw *g* is entered; by this means the rail is very firmly 85 connected to the bed and but little noise is produced by the concussion of the ball on the cushion.

In those portions of the bed where the slabs *b*, *b*, abut against each other at their edges as seen at *h*, Fig. 1, I make use of an 90 anchor piece *i*, screwed onto the frame and the glass is beveled at this point as shown, the object of these anchors being to prevent the slab sliding on the frame.

Having thus described my said invention 95 and the peculiarities of the same a repetition of the advantages resulting therefrom is unnecessary.

What I claim as my invention and desire to secure by Letters Patent is—

1. Constructing the beds of billiard tables of slabs of glass substantially as and for the purposes specified.

2. I claim the clips *c, c*, taking the beveled edges of the slab to retain the same as described and shown.

3. I claim the block *e*, receiving the screws

g of the cushion rail as and for the purposes 10 described.

In witness whereof I have hereunto set my signature this sixth day of October, 1858.

DANIEL D. WINANT.
